UNITED STATES PATENT OFFICE.

ERNEST W. SEAHOLM AND HARLEY J. EARL, OF DETROIT, MICHIGAN, ASSIGNORS TO
GENERAL MOTORS CORPORATION, OF DETROIT, MICHIGAN, A CORPORATION OF
DELAWARE.

DESIGN FOR A MOTOR-VEHICLE FRONT ASSEMBLY.

Application filed November 15, 1926. Serial No. 19,737. Term of patent 14 years.

To all whom it may concern:

Be it known that we, ERNEST W. SEAHOLM and HARLEY J. EARL, citizens of the United States, and residents of Detroit, county of Wayne, State of Michigan, have invented a new, original, and ornamental Design for Motor-Vehicle Front Assembly, of which the following is a specification, reference being made to the accompanying drawing, forming a part thereof.

In the drawing, Figure 1 shows our new design in side elevation.

Figure 2 shows the design in front elevation.

We claim:

The ornamental design for a motor vehicle front assembly as shown.

ERNEST W. SEAHOLM.
HARLEY J. EARL.
